UNITED STATES PATENT OFFICE.

HARRY L. SMITH, OF MINNEAPOLIS, MINNESOTA, ASSIGNOR TO SMITH SYSTEM HEATING COMPANY, OF MINNEAPOLIS, MINNESOTA, A CORPORATION OF MINNESOTA.

PORTABLE LAVATORY.

Application filed September 1, 1927. Serial No. 216,872.

My invention has for its object to provide a portable self-contained lavatory and water supply intended for general use, but especially adapted for use in rural schools and 5 the like that are not equipped with running water.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a perspective view of the invention;

Fig. 2 is a view principally in vertical section taken on the line 2—2 of Fig. 1; and

Fig. 3 is a transverse horizontal section 20 taken on the line 3—3 of Fig. 2.

The invention includes a wall panel 4 comprising a commercial board 5 having a facing 6 of sheet metal secured thereto by having edge portions of said facing folded over the 25 edges of the board 5 and onto the back thereof, as shown in Figs. 2 and 3.

The panel 4 is provided with a plurality of holes 7 for screws or other attaching devices for securing the panel 4 to one of the 30 walls of a room. Mounted on the panel 4 is a lavatory formed from sheet metal, preferably nickel-plated copper or other non-rusting material, and comprising a semi-cylindrical basin 8 having a flat back that is extended materially above the rim of the 35 basin 8 and secured by screws 9 to the panel.

The basin 8 is further supported by a bracket 10 in the form of an inverted semi-conical sheet metal member, the flat side of 40 which is turned toward the panel 4 and provided with inturned flanges 11 riveted or otherwise secured to said panel. The base of the bracket 10 has the same contour as the basin 8, at the bottom thereof, and is 45 secured thereto by a bead or other fastening means 12.

The lavatory also includes a drain for the basin 8 in the form of a commercial fitting comprising a vertical pipe 13 which extends through an aperture in the bottom of the basin 8 and a depending sleeve-like boss 14 rigidly secured to the bracket 10. The pipe 13 has on its upper end an upstanding flange 15 mounted in a depression in the bottom 55 of the basin 8 with its upper face flush with

the bottom of the basin 8 and soldered or otherwise secured thereto to form a watertight joint between the pipe 13 and basin 8. A nut 16 has screw-threaded engagement with the lower end of the pipe 13 and is 60 provided with a washer or shoulder 17 which bears against the lower end of the boss 14 and thereby rigidly connects the basin 8 and bracket 10.

A nipple 18 for a hose connection, not 65 shown, is attached by a union 19 to the lower end of the pipe 13. Such a hose connection may be extended outside of the building for discharging water from the basin 8 away from the building. In place of the nipple 70 18, the pipe 13 may have attached thereto a trap with connections to a water disposal system.

Mounted on the panel 4 above the lavatory is a substantially semi-cylindrical water supply tank 20 having a flat back rigidly secured by rivets 21 to the panel 4, and it will be noted that these rivets are located above the water level $\approx$ so that there is not danger of leakage. The tank 20 is provided with an 75 inverted semi-conical bottom 22 and a semi-conical cover 23 having a depending flange 24 telescoped into the tank 20, and an outstanding shoulder 25 that rests on the rim of the tank 20 and forms a tight joint between 80 the tank 20 and its cover 23. Said cover 23 is provided with a handle 26.

A water pipe 27 leads from the tank 20 at the apex of its bottom 22. The water pipe 27 includes an elbow 28 at the lower end 90 thereof and which elbow is secured by screws 29 to the panel 4 and thereby rigidly holds said pipe in position and also assists in supporting the tank 20 from the panel 4. Attached to the outer end of the horizontal portion of the pipe 27 is a faucet 30. A volume flow regulating valve 31 is interposed in the vertical section of the water pipe 27.

The purpose of the valve 31 is to permit only a given discharge of water from the 100 faucet 30 even when said faucet is wide open and thereby prevent waste of water. The lavatory may be provided with the customary plug or stopper, not shown, for the drain thereof.

The above described portable lavatory and water supply is so designed that it may be shipped complete with all parts assembled at the time the same leaves the factory, and it is only necessary to fasten the same in position 110

tion on a wall by means of screws inserted through the holes 7.

It will be noted that a wrench is required to operate the valve 31 so that said valve can not be tampered with to change the flow of water from the supply tank 20.

What I claim is:

1. The combination with a lavatory, of a supporting bracket for the lavatory in the form of an inverted substantially semi-conical bracket supporting the basin of the lavatory on its base, a drain for the basin including a pipe extending through an aperture in said basin and a depending sleeve-like boss on the bracket and having a flange on its upper end resting on the bottom of the basin with a water-tight joint therebetween, and a shouldered nut having screw-threaded engagement with said pipe and engaging the lower end of the sleeve-like boss as a base of resistance.
2. A new article of manufacture comprising a wall panel, a lavatory mounted on the panel, a water storage tank mounted on the panel above the lavatory, a water supply pipe leading from the tank and having a faucet arranged to discharge into the basin

of the lavatory, said lavatory being substantially semi-cylindrical in cross section with a flat back, and an inverted substantially semi-conical bracket attached to the wall panel and supporting the lavatory on its base, said lavatory having a drain pipe extending through the bracket and rigidly connecting said lavatory and bracket. 30

3. A new article of manufacture comprising a wall bracket, a lavatory mounted on the panel, a water discharge tank mounted on the panel above the lavatory, a water supply pipe leading from the tank and having a faucet arranged to discharge into the basin of the lavatory, said lavatory being substantially semi-cylindrical in cross section with a flat back and having an inverted substantially semi-conical bracket attached to the panel and supporting the lavatory on its base, said bracket having a depending sleeve on its side, said lavatory having a discharge pipe extending through said sleeve, and a nut on said pipe engaging the lower end of the sleeve and operative to draw the lavatory and base together. 40

In testimony whereof I affix my signature.
HARRY L. SMITH. 45
